UNITED STATES PATENT OFFICE.

HERBERT E. PENNEY, OF MINNEAPOLIS, MINNESOTA, ASSIGNOR TO W. S. NOTT COMPANY, OF MINNEAPOLIS, MINNESOTA, A CORPORATION.

STEAM-GENERATOR.

SPECIFICATION forming part of Letters Patent No. 717,915, dated January 6, 1903.

Application filed August 18, 1902. Serial No. 120,015. (No model.)

To all whom it may concern:

Be it known that I, HERBERT E. PENNEY, a citizen of the United States, residing at Minneapolis, county of Hennepin, and State of Minnesota, have invented certain new and useful Improvements in Steam-Generators, of which the following is a specification.

My invention relates to vertical steam-generators of the sectional water-tube type.

10 The object of the invention is to dispense with the usual water-leg formed between vertical shells and to substitute therefor a water-drum composed of communicating horizontal headers and upright return-pipes in 15 circular arrangement and connected with headers or a steam-ring above and to provide in the interior a series of vertical separately-removable manifolds or tube-sections composed of headers and inclined tubes.

20 My improvements are illustrated in the accompanying drawings, in which—

Figure 1 is a vertical sectional view of a steam-generator embodying my improvements. Fig. 2 is a horizontal section of the 25 same on the irregular line $w w$ of Fig. 1. Fig. 3 is a top or plan view of Fig. 1 with the hood and chimney removed, and Figs. 4 and 5 are enlarged detail views of the upper and lower headers and their connections.

30 In the drawings, 1 designates a cylindrical inclosing shell; 2, the smoke-stack; 3, the hood over the top of the generator; 4, the fire-grate, (shown in broken lines,) and 5 the fire-door. These features may be of any 35 usual or suitable construction. In the lower portion of the shell is a series of horizontal segmental headers 6, connected together in a circle by short coupling-pipes 7, to provide the water-space or water-drum of the generator. Supply-pipes 8 are connected to the water-drum at any desired points. To the top of the headers 6 of the water-drum is connected a series of vertical pipes 9, that connect with the under side of a series of upper 45 headers 10, which may correspond in form and arrangement with the lower headers 6 and may be similarly connected together to form a steam-ring or may be independent of one another.

50 In using the term "steam-ring" herein I mean to include both of the suggested ar-

rangements. The pipes 9 are for the return of water from the steam-ring to the water-level below. These pipes may be placed as close together as desired to prevent the escape of any great amount of heat from the combustion-chamber within their circle.

Within the circle of the return-pipes is a series of manifolds or tube-sections arranged in parallel vertical planes, and each tube-section consists of a pair of opposite vertical headers 11 and inclined connecting-tubes 12, the tubes of each section preferably inclining in opposite direction from those of adjoining sections. The headers shown in the drawings are made up of a plurality of short sections placed end to end and united by removable pipe-couplings 13. The inner surfaces of the headers are provided with tapped inclined sockets 14, arranged in staggering order, to receive the threaded ends of the water-tubes 12. The lower ends of the headers are connected by detachable pipe-couplings 15 with the water-drum and their upper ends are detachably connected by bent-pipe connections 16, arranged to discharge downward into the steam-ring. The pipe connections 15 and 16 may be of any usual or suitable construction adapted to be conveniently disconnected to permit the removal of a tube-section.

A steam-drum 17 of any desirable form (shown as a short upright cylinder in the drawings) is arranged centrally over the series of tube-sections. The headers 10 of the steam-ring are connected with the lower portions of this drum by pipes 18, and a steam-discharge pipe 19 is connected to its upper portion.

By disconnecting the tube-section connections 15 and 16 with the water-drum and steam-ring the selected tube-section can be readily removed, and by also disconnecting a selected water-drum and steam-ring section from adjoining sections such section, including its return-pipes, can be readily removed.

In operation water is supplied from the water-drum to the lower headers of the tube-sections, and when steam is generated it rises through the tubes and headers and, together with whatever water it may carry over, discharges downward into the steam-ring, and

the steam passes off through the pipes 18 to the steam-drum, while the water descends directly through the pipes 9 toward the water-drum to the water-level of the generator.

5 Having described my invention, what I claim, and desire to secure by Letters Patent, is—

1. In a steam-generator, the combination with an inclosing shell, a water-drum composed of segmental sections, a steam-ring composed of corresponding sections, and a series of return-pipes connecting said drum and ring sections; of a series of interior tube-sections comprising opposite vertical headers 15 and tubes connecting them, detachable connections leading from the water-drum to the lower ends of the headers, and detachable pipe connections leading from the upper ends of the headers and discharging downward 20 into the steam-ring, substantially as set forth.
2. In a steam-generator, the combination with an inclosing shell, a water-drum composed of segmental sections, a steam-ring composed of corresponding sections, and a series of return-pipes connecting said drum and ring sections; of a series of interior 25 separately-removable tube-sections arranged in parallel vertical planes, each tube-section comprising vertical headers and connecting 30 tubes, detachable connections leading from the water-drum to the lower ends of the headers, and detachable pipe connections leading from the upper ends of the headers and discharging downward 35 into the steam-ring, substantially as set forth.
3. In a steam-generator, the combination with an inclosing shell, a water-drum, a steam-

ring, and a series of return-pipes connecting such drum and ring; of a series of separately-removable tube-sections, each tube-section 40 comprising opposite vertical headers composed of a plurality of short sections placed end to end and united by removable couplings and inclined tubes connecting opposite header-sections, the inclinations of the 45 tubes being opposite in adjacent tube-sections; detachable connections leading from the water-drum to the lower ends of the headers, and detachable pipe connections leading from the upper ends of the headers and discharging downward into the steam-ring, substantially as set forth.

4. In a steam-generator, the combination with an inclosing shell, a water-drum, a steam-ring, and a series of return-pipes connecting 55 such drum and ring; of a series of separately-removable tube-sections, each tube-section comprising opposite vertical headers and inclined tubes connecting them, the inclinations of the tubes being opposite in adjacent 60 tube-sections; detachable connections leading from the water-drum to the lower ends of the headers, and detachable pipe connections leading from the upper ends of the headers and discharging downward into the steam- 65 ring, substantially as set forth.

In testimony whereof I have signed my name to this specification, in the presence of two subscribing witnesses, this 7th day of August, 1902.

HERBERT E. PENNEY.
